UNITED STATES PATENT OFFICE.

CLAUD D. CURRY AND ALBERT W. LINN, OF MEMPHIS, TENNESSEE.

MACHINE FOR ASSEMBLING NEWSPAPER PARTS.

No. 881,305.

Specification of Letters Patent. Patented March 10, 1908.

Application filed July 30, 1906. Serial No. 328,379.

To all whom it may concern:

Be it known that we, CLAUD D. CURRY and ALBERT W. LINN, citizens of the United States, residing at Memphis, in the county of 5 Shelby and State of Tennessee, have invented new and useful Improvements in Machines for Assembling Newspaper Parts, of which the following is a specification.

This invention is a machine for associating different parts of a newspaper or other printed matter, such parts being folded preparatory to delivery.

In newspapers printed in several parts, on different presses, it is common to assemble 15 the parts after they are folded, by placing one part within another. This has heretofore been done by hand, and is known as "stuffing". When done by hand it is slow work, and requires a large number of hands.

20 The object of this invention is to provide means for quickly doing this work by machinery. The machine embodies devices for feeding the parts of the newspaper which are to be stuffed or associated, and pneumatic 25 means for opening the fold of the outer part so that the inner part or supplement may be placed within the same.

The machine is illustrated in the accompanying drawings, in which

30 Figure 1 is a side elevation thereof. Fig. 2 is a vertical cross section. Fig. 3 is a detail in perspective of what will hereafter be called the "opener". Fig. 4 is a detail in side elevation of the gearing for driving the feeding device. Fig. 5 is a detail in perspective of the feeding device or conveyer. Fig. 6 is an enlarged detail in side elevation of part of the feeding mechanism.

Referring specifically to the drawings, 6 indicates the side frame of the machine, of 40 proper form to suit the working parts and accommodate the gearing. The outer and inner parts of the paper, which are to be assembled or stuffed together, are fed to opposite ends of the machine, from which the respective parts are alternately carried to the assembling devices, as described hereinafter.

45 Each feeding mechanism consists of an endless chain belt 7, running around shafts 8 and 9 between side boards 10. This chain carries a series of cross-bars 11 which are connected to the chain by hooks 12, and at the ends these cross-bars have rollers 13 which run in grooves 14 on the side pieces 10. The 55 cross-bars 11 have holes 15 adapted to receive pins 16 projecting from the lower edge

of boards 17 which are thus supported in an upright position upon the bars and between the side pieces 10. The inner end of the conveyer thus formed is turned up toward the vertical, as shown in the drawings, so that the papers are delivered at the end of the conveyer in a substantially horizontal position. The folded papers are placed in the conveyer with the folded edges or butts 60 down, resting upon strips 18 supported between the side pieces 10 and extending lengthwise. The spaces between the boards 17 are thus packed full of the folded papers standing edgewise, and as the belt moves the 65 papers are fed to the inner or upper end of the conveyer. The boards 17 are removed as fast as they reach the upper end of the conveyer and replaced by the attendant at the lower or outer end on another bar. The 70 papers are thus delivered at the upper end of the conveyer in a substantially horizontal position, with the butts or second folds of the papers directed inwardly toward the main body of the machine. The 75

Each conveyer is driven with an intermittent motion, at slow speed by means of gearing as follows: On a driven shaft 30 is a beveled gear 31 meshing with a beveled gear 32 on a shaft 33 which has a worm 34 meshing 80 with a gear 35 on a shaft 36, and the gear 35 is connected by a rod 37 to a lever 38 carrying a pawl 39 which engages a ratchet wheel 40 on the shaft 8 of the conveyer. The connecting rod 37 is adjustably connected to the 85 gear 35 by means of a block in a radial slot 41, whereby the throw of the pawl lever, and consequently the feed motion given the ratchet, can be varied. The gearing referred to is supported by proper brackets on the inner side of one of the side frames 6. The parts of the paper thus received at opposite ends of the machine are alternately delivered, one by one, by similar devices consisting in each instance of the parts to be now 90 described. 50 indicates an air-trunk pipe connected to an exhaust fan 51. Said pipe is supported above the machine with an arm or branch located over the inner end of each conveyer, and each arm of the air-trunk has 95 a series of depending branch pipes 52 on which are sleeves 53 slideable up and down to and from the papers, indicated at X, at the end of the conveyer. The sleeves are carried by cross-bars 54 connected at their ends to 100 uprights 55 which slide up and down in guides 56, the upward motion being pro-

duced by cams 57 on the shaft 30, said cams working under the lower ends of the uprights. The sleeves and the uprights drop by gravity and are lifted by the cams, and 5 the suction through the pipes causes a paper to be lifted from the conveyer at each operation. The paper thus lifted is brought against the carrying tapes, and to assist in this action a roller 58 is employed. This 10 roller is guided at its ends in grooves 59 formed in the side frames of the machine, these grooves being located adjacent to the upper end of the conveyer. The roller 58 moves back and forth in the grooves, being 15 connected at its ends by links 60 to levers 61 which are pivoted at 62 to brackets on the frame and which are connected by rods 63 to one of the cross-bars 54. The lever 61 and links 60 form a sort of toggle, and on the 20 downward motion of the bars 54 and sleeves 53 are extended so that the roller 58 is moved downwardly and inwardly in the grooves 59 beyond the butts of the papers, as indicated on the right side in Fig. 2, and when the bars 25 54 and sleeves are lifted the roller 58 is drawn inwardly and upwardly under the paper which at that time is being lifted by the suction devices, as shown on the left, in Fig. 2. The effect of this is to press said paper 30 against the upper tapes 70. This action is assisted by means of loose elongated wire loops 64 which extend around the roller 58 and also around in grooves in a tape roller 80. The loops 64 are free to swing as the roller 58 35 moves back and forth, and, as will be seen, they come up on the lift against the under side of the paper and press the same against the upper tapes 70 and also act as a bridge or guide to direct the papers above the roller 80 40 and in between the upper and lower tapes.

The upper tapes 70 run in the direction shown by the arrow, around a roller 71 located above the end of the conveyer, and thence over guide rollers 72, 73, 74 and 75 45 and a tension roller 76. The lower tapes 81 pass over the roller 80, heretofore referred to, thence over guide rollers 83 and 84, guide roller 82, and tension roller 83. The tapes are spaced apart, and the upper tapes are so 50 arranged that the suction sleeves 53 work up and down between the tapes, where they overhang the lower tapes above the conveyer, so that the papers are lifted to contact with said overhanging or projecting part of the upper tapes, which then carry the paper 55 in between the upper and lower tapes and deliver the same to the associating mechanism. Located between the delivery or inner ends of the tapes leading from opposite ends of the 60 machine is a V-shaped guide 84^a, conveniently formed of sheet metal, to properly direct the parts to the associating device.

At 90 are indicated air-trunks extending 65 across the machine and provided with branch pipes 91 extending oppositely toward each

other. Upon the branch pipes are sleeves 92 at the inner ends of each set of which is a plate 93, through which the sleeves open, and these plates are hinged to frames 94 which extend downwardly from said plates and have at their lower edges pins 95 which act as pivots in elongated bearings 96 in each side frame of the machine. The plates 93 and the frames 94 move to and from each other, such movement being produced by 70 cams 97 on shafts 98 which operate levers 99 connected by links 100 to the plates 93. 75

Working back and forth under the lower edges of the frames 94 are a set of fingers 101 projecting from a bar 102 which has a rod 103 extending to contact with a cam 104 on one of the shafts 98. Said rod is supported by a cross piece 105. The cam 104 acts to advance the bar 102 so that the fingers 101 project across the space between the lower edges of the frames 94. The fingers are retracted by means of a coil spring 106, around the rod 103. Located below the fingers 101, under the mouth of the opener, is a pair of delivery rolls 107, and below these is an ordinary delivery 80 belt 108, with a fly 109 for laying down the papers as they are delivered. 85

Each of the trunks 90 is provided with a damper 110, to cut off the exhaust, and said dampers are automatically operated to be in 90 open position when the sleeves 92 are advanced and to close as said sleeves retract. The dampers are pivoted in the trunks and connected by links 111 and crank arms 112 to the sleeves 92. 95

The tapes and other devices are all driven by suitable gears which, it is thought, requires no description further than that which has been given, since it is a matter of mechanical arrangement, but the feeding devices are so arranged and actuated that the parts of the paper to be stuffed together are delivered alternately from the opposite ends of the machine. Thus, in operation, an outer part is delivered from one conveyer and is carried by the tapes on one side and dropped, butt or fold down, between the frames 94, and stops upon the fingers 101, at which time the frames 94 and plates 93 are approaching each other and the fingers 101 are advanced. The 100 said outer part of the paper being in position between the frames 94 and plates 93, the further advance of the plates causes the suction sleeves to come against opposite folds of the paper. The sleeves are then retracted, causing the frames 94 to swing apart and causing the newspaper section to open at the top or upper edge, to a V-shape, the fold resting on the fingers 101. This action is assisted by means of a blast which blows continually from a slotted opening 120 transversely between the frames 24. The blast is supplied through a pipe 121 from the fan 51. The papers are so fed that this blast will be 110 directed toward the first fold or edge of the 120 115 125 130

paper and will thus tend to spread or open the paper and flatten out the free ends of the sheets. The outer part of the paper being thus delivered into the opener, and opened, 5 the inner part or supplement is delivered from the other end of the machine and dropped within the fold of the outer section. The fingers 101 are then retracted, which allows the associated parts of the paper to drop to 10 the delivery belt 108, on which the papers are piled by the fly and from which they may be removed as desired. These operations are repeated successively. It will be seen that 15 no hand work is necessary, except to keep the feeders supplied with the newspaper sections.

We claim:

1. In a machine of the kind stated, the combination with an opener having opposite frames which swing to and from each other, 20 to open the fold of paper, of means to alternately deliver outer and inner folded paper sections to the opener, and means to actuate the opener to open the outer section when it is delivered thereto, to allow the inner section 25 to be inserted within the same.
2. In a machine of the kind stated, the combination with an opener and means to operate the same to open a folded paper, of a V-shaped guide leading to the opener, and 30 opposite feed mechanisms leading to opposite sides of the guide, and means to actuate the same to alternately feed outer and inner paper sections from the respective mechanisms to the guide.
3. In a machine of the kind stated, an 35 opener comprising opposite frames pivoted at their lower edges and arranged to swing toward and from each other, and suction tubes connected to each frame at the upper edge thereof and movable therewith toward and from each other.
4. An opener comprising opposite frames

pivoted near together at their lower edges and arranged to swing toward and from each other, opposite suction tubes connected 45 to each frame and movable therewith, and means to cut off the suction after each opening movement.

5. In combination, a V shaped opener the sides of which are spaced apart, and pivoted 50 at their lower edges to swing toward and from each other, suction tubes carried by the opposite sides and having means to govern the suction therethrough, means to supply successively outer and inner paper 55 sections downwardly into the opener, the sides being actuated to swing open after the outer section is supplied, to allow the inner section to be inserted within the same, a movable support under the space at the 60 bottom of the opener, and means to withdraw intermittently the support, to allow the associated sections to discharge from the opener.

6. An opener comprising opposite pivoted 65 frames, means to swing the same toward and from each other, and pneumatic devices operating between said frames and adapted to open a folded paper therebetween.

7. An opener comprising opposite frames 70 pivoted at their lower edges and arranged to swing toward and from each other, and means to deliver a blast of air transversely between said frames, to blow open a folded paper between the frames, as said frames 75 swing open.

In testimony whereof we have signed our names to this specification in the presence of two subscribing witnesses.
